GRAVE MARKER

Filed March 21, 1928

FIG. 1

FIG. 3
INVENTOR:

BY R. H. POLLARD
H. J. Sanders
ATTORNEY

UNITED STATES PATENT OFFICE

ROBERT H. POLLARD, OF CHICAGO, ILLINOIS

GRAVE MARKER

Application filed March 21, 1928. Serial No. 263,502.

This invention relates to improvements in grave markers. One object is to provide a very substantial and durable marker that is of neat appearance, comparatively inexpensive to manufacture and that can be set in position without difficulty.

With the foregoing and other objects in view the invention consists in the combination and arrangement of parts to be herein fully described, particularly pointed out in the claim and illustrated in the accompanying drawing which forms a part of this application and in which—

Fig. 1 is a view in elevation of a marker constructed in accordance with this invention.

Fig. 2 is a fragmentary view, partly in section and partly in elevation, the memorial section being turned at an angle to the supporting pedestal.

Fig. 3 is a top plan view of the marker, the memorial section being removed.

Like reference characters denote corresponding parts through the several views.

The present invention comprises a vertical post tapered from its upper to its lower end, a horizontal ledge portion integral with said post at the upper end thereof, and a pedestal rising from said ledge and tapered therefrom to its upper end, said pedestal and ledge being integral and all of said portions having imbedded therein a suitable reinforcing material. The post, ledge and pedestal are preferably formed of concrete or like material and are of very strong and durable construction.

The memorial section of the marker comprises a bronze plate or tablet adjustably connected to and supported by a bronze standard received and supported in a recess formed in the pedestal. The adjustability of the plate permits its disposal at such an angle to the pedestal as may be most desirable to permit reading of the indicia thereon to the best advantage or to add most to the general appearance of the marker. It is intended to have the indicia die-stamped upon the tablet or cast therewith although other methods may be resorted to if subsequently found more expedient.

The reference numeral 1 denotes the post or stake tapered from its upper to its lower end 2, said stake at its upper end bearing the horizontal ledge 3. The stake is imbedded in the earth up to the ledge 3 which rests upon the ground. Rising above the ledge 3 is the pedestal 4 tapered from the ledge to its top-most point 5, said pedestal, ledge and stake being provided with reinforcing rods or wire mesh 6.

The pedestal is formed with a central vertically disposed cavity to receive the bronze standard 7 that is connected by the friction hinge 8 to the bracket 9 carrying the tablet 10 having thereon the indicia 11. The hinge 8 is of that type that is yieldingly adjustable so that it will remain in any adjusted position.

What is claimed is:—

In a grave marker, a tapered stake for disposal wholly in the ground, a ledge at the upper end thereof of greater diameter than said stake for disposal flat upon the ground, a pedestal wholly above the ground and rising from said ledge, reinforcing material imbedded in said members, said pedestal being formed with a central vertically disposed recess, a standard fixed in said pedestal recess, a memorial tablet, a supporting bracket therefor, and a friction hinge connecting said bracket and standard.

In testimony that I claim the foregoing as my own I have hereto affixed my signature.

ROBERT H. POLLARD.
